ELIZABETH A. FRANCKE, OF NEW YORK, N. Y.

DOLL MADE OF FIBROUS MATERIALS.

Application filed February 24, 1926. Serial No. 90,235.

This invention relates to an improvement in dolls and more particularly to improvements in dolls made of fibrous materials such as woolen, cotton or silk yarn.

5 A particular object of my invention is the provision of a doll which can be substantially constructed from one hank of yarn with a minimum of labor and material and with which various interesting figures can 10 be produced.

Further objects of the invention will be apparent from the specification and drawings in which—

Fig. 1 shows a hank of yarn which serves 15 as the raw material for the manufacture of a single doll.

Fig. 2 shows the same hank of yarn partly modified to form a doll.

Fig. 3 is a perspective view of the finished 20 article of manufacture.

Fig. 4 is a side view of the doll shown in Fig. 3.

Fig. 5 is a perspective view of a thinner hank of yarn than that shown in Fig. 1, 25 which has to be folded in the middle in order to form a doll with a body of sufficient thickness.

Fig. 6 shows the front of the hank shown in Fig. 5.

Fig. 7 is a side view and shows the lower 30 part of the hank when folded.

When the yarn is used as shown in Fig. 5, no cutting is necessary to form the legs and gives further opportunities for variation in 35 the form of the dolls made.

As the first step in the process of manufacture, the hank of yarn shown in Fig. 1 is cut in two at the bottom thereof and the top portion is bound together to form the head.

40 When enough material has accumulated in the hand to form the head, a string is tied around the hank and knotted as shown in Fig. 2. To form the arms a portion of the hank of yarn is cut or severed as at 1 and the

45 waist portion is formed by tying a knot around the middle portion of the hank as shown in Fig. 2. The legs are formed by cutting off the ends of the hank of yarn as

shown at 2 and fingers and toes may be formed in the same fashion by continuing 50 the division of the respective hanks to form the toes and fingers as will be clearly seen from an examination of Figs. 3 and 4. Eyes are produced in the doll by sewing therein yarn of a contrasting color; the eyelashes 55 and eyebrows and the other features are similarly formed. Hair can be attached to the head by sewing thereon yarn of a different color from that composing the head and the doll may also be ornamented with jewelry, 60 with belts or with other additions, without departing from the spirit of the invention.

It is apparent that in this fashion dolls may be very easily made with very simple means and capable of an endless number of 65 modifications.

Having fully described my invention, what I claim is:

1. The method of manufacturing a doll by taking a continuous hank of yarn composed 70 of a large number of threads, cutting the hank at one point, encircling the hank near the end of the loop formed by the uncut portion in order to form the head of the doll selecting and separately tying other portions 75 of the hank with annular retaining members so as to form the limbs and body of the doll entirely from the threads of the yarn.

2. The method of forming a doll by taking a continuous hank of yarn composed of many 80 threads, cutting said hank at one point, gathering the uncut loop of the hank into a ball to form the head, tying said loop and successively selecting and separately tying other portions of the hank to form the limbs 85 and body of the doll.

3. The method of forming a doll by taking a continuous hank of yarn composed of many threads, cutting said hank at one point, gathering the uncut loop of the hank 90 into a ball to form the head, tying said loop and successively selecting and separately tying other portions of the hank to form the body, the limbs, fingers and toes of the doll.

In testimony whereof I affix my signature.
ELIZABETH A. FRANCKE.
